UNITED STATES PATENT OFFICE.

JACOB YOUNG, OF WINTHROP, MASSACHUSETTS.

STILL.

Application filed January 17, 1922. Serial No. 529,839.

This invention relates to a still especially adapted for separating a more volatile from a less volatile liquid by distillation, and the object of the invention is to provide an apparatus by which a more complete separation may be effected than can usually be attained by a single operation of a still of simple construction.

While the still is of general application, it will for convenience be described in connection with the operation of separating a more volatile from a less volatile liquid.

Fig. 1 is a sectional elevation of a still embodying this invention; and

Figs. 2, 3 and 4 sectional details thereof on lines X², X³ and X⁴ of Fig. 1 respectively.

The retort or boiler 2 may be of any suitable or usual construction, being adapted to contain the material to be operated upon and to be heated in any suitable manner as for example by the burners indicated at 3. A thermometer 4 is provided to indicate the temperature of the material in the boiler.

The vapor rising from the heated material passes through the pipe 5 into a primary condensing chamber 6, the construction of which is one of the distinctive features of the invention and will be described more in detail later on, said condensing chamber being contained in an upwardly inclined portion 50 of the pipe, constituting a continuation of the pipe 5 and being surrounded by a cooling jacket 7.

In the primary condensing chamber 6, it is intended that only the less volatile liquid shall be condensed, and owing to the inclination of the pipe 5, 50, it will be returned to the boiler, while the vapor of the more volatile liquid passes on as vapor into the pipe portion 51 which leads to a downwardly extending portion 20 constituting a secondary condensing chamber which extends downward to a delivery point 52 through which the more volatile liquid condensing in the secondary chamber 20 flows into any suitable receiver.

The pipe 5, 50, 51, 20, and condensing chambers contained in, or constituting a portion thereof, thus constitute a continuous vapor duct from the retort 2 to the contracted delivery aperture at 52.

The secondary condenser comprises a cooling jacket 70 surrounding the vapor duct and adapted to cool the same and the said vapor duct is provided with a longitudinal helical partition 22 which tends to give the

vapor passing therethrough a rotary movement and to bring it more thoroughly under the effect of the cool wall of the duct than would be the case if the passage through the duct were perfectly free.

The jacket 70 is adapted to receive cooling water through the pipe 72 entering at its lower end and under control of a valve 73 and said water becomes warmer in its passage upward through the jacket 70 and is delivered from the upper end thereof through the pipe 74.

A portion of the water, somewhat warmed in its passage through the jacket 70, is permitted to flow through pipe 75 into the lower side of the jacket 7 of the primary condensing chamber near the higher end thereof, being permitted to escape through the pipe 76 from the upper side of the jacket 7 but nearer the lower end thereof, the arrangement being such as to keep the jacket 7 completely filled with the cooling liquid.

In operation, the liquid in the boiler 2 is subjected to moderate heat which should impart a temperature between the boiling points of the liquids to be separated, but which will result in a considerable portion of the less volatile liquid being vaporized together with the more volatile liquid, so that the mixed vapor will pass through the pipe 5 into the primary condenser 6 which is only moderately cooled so that while effecting the condensation of the vapor of the less volatile liquid, it will permit the more volatile material to remain as vapor to be carried through the pipe 51 into the secondary condenser 20, 70 where it will be condensed and delivered as liquid from the apparatus.

The less volatile liquid condensing in the primary condenser 6 will by reason of the inclined position thereof, tend to flow back into the boiler 2.

In the operation as thus far described, it is not possible or practicable to maintain such temperature in the primary condenser as will result in the condensation of the vapor of the less volatile liquid only, and a portion of the vapor of the more volatile liquid will also condense, and if there were nothing further than what has already been described, some of it would flow back with the less volatile liquid into the boiler 2, and moreover, a portion of the vapor of the less volatile liquid would be carried over into the secondary condenser, and would be con-

densed therein and discharged with the more volatile liquid.

In order to obviate such action, the primary condenser 6 is provided with what may be regarded as a re-vaporizing appliance shown in this instance as contained in a tubular body 30 adapted to be introduced into the inclined portion 50 of the duct, and provided with baffle plates 31, 32, alternately rising from the lower wall nearly to the upper wall of the tube, and depending from the upper wall nearly to the lower wall so as to form a sinuous passage for the vapor, through the upwardly inclined portion of the vapor duct constituting the primary condenser.

In order to permit the liquid which condenses in the primary condenser to flow back along the lower side wall of the duct without having to pass over the upper edge of the baffle plates rising from the said lower wall, the said baffle plates which rise from the said lower wall, or some of them, are perforated, or made of some foraminous material as shown, the result being that the flow of liquid back towards the boiler is impeded and the liquid tends to accumulate to a slight depth at the upper side of each baffle plate.

This construction makes in effect a series of chambers or compartments along the bottom of the primary condenser in which the liquid condensed in said primary condenser accumulates, so that while the still is in operation, there will be a small pool of liquid in each such compartment, on the upper or higher side of each baffle plate 31 rising from the lower wall of the upwardly inclined portion of the vapor duct constituting the primary condenser.

The function of the upper baffle plates 32 is to retard the flow of vapor and to direct it repeatedly towards the pools of condensate accumulated in the chambers above the lower plates 31.

The depth of each pool would depend upon the aggregate area of the openings in the foraminous plates, and by having said plates, or some of them, imperforate for a certain height from the lower edges, as shown at 310, the pools, or some of them, may be deep enough to have the upper baffle plates 32 dip into the liquid so that the vapor will have to bubble through the liquid at one or more points.

The temperature in the vapor tube or primary condenser 6 due to the jacket 7 should not be below the boiling point of the more volatile liquid, and the result will be that while some of the more volatile liquid will condense with the less volatile liquid, the condensed mixture will be retained in the receptacles and thus retarded on its way back to the boiler, and while thus retained it will be subject to the action of the vapor

on its way from the boiler to the secondary condenser, the temperature of which will be sufficient to re-vaporize the more volatile liquid, the vapor of which will then pass over into the secondary condenser.

Thus while it is not practicable to make a complete separation of the more volatile from the less volatile liquid at the first boiling, but a portion of the less volatile liquid will also be vaporized, and while it is impracticable at a single simple condensing operation to effect the separation by condensing the less volatile material while leaving the more volatile in the form of vapor, the repeated re-vaporizing action that takes place in the pools in the successive chambers of the primary condenser will be effective to obtain an almost complete separation of the more volatile from the less volatile material at a single operation of the still, that is, a single passage of the vapor through the primary and secondary condensers.

For the most satisfactory operation, it is necessary that the temperature of the liquid surrounding the primary condenser should be maintained at such temperature that while cooling the vapor below the boiling point of the less volatile liquid, it will not cool below the boiling point of the more volatile liquid which should pass through the primary condenser in the form of vapor.

The desired temperature in the cooling jacket of the primary condenser is maintained automatically in accordance with the present invention as follows:

As before stated, the water for cooling the jacket of the primary condenser is taken by the branch pipe 75 from the discharge pipe 74 from the jacket of the secondary condenser, in the action of which the water delivered at 74 may be brought to approximately the temperature desired in the cooler part of the jacket of the primary condenser.

The cooling effected depends to some extent upon the rapidity of flow through the jackets, a slower flow carrying away less heat and consequently causing the water to attain a higher temperature than when the flow is more rapid.

The flow through the pipe 75 into the jacket of the primary condenser is controlled by a valve 80 automatically operated by a thermostatic couple 81 which is responsive to the temperature of the vapor passing through the connecting duct 51 from the primary to the secondary condenser, at which point the temperature may be observed by a thermometer 40.

If the temperature rises above the point found to be most effective at this place in the apparatus, the increase in temperature of the thermostatic couple 81 will cause a wider opening of the valve 80, and will thus bring about a more rapid flow of liquid through the pipe 75 and jacket 7 of the primary con-

denser, thus reducing the temperature ther-
in until the vapor passing through the con-
necting duct 51 is at the most effective tem-
perature.

- 5 If on the other hand, the temperature is
too low so that an excessive amount of the
more volatile liquid is condensed in the pri-
mary condenser, the temperature in the con-
necting passage 51 will fall and by its action
10 on the thermostatic couple 81 will cause a
less opening of the valve 80 thus permitting
a less rapid flow of water through the jacket
of the primary condenser so that its temper-
ature will rise to the desired point.
15 Any other regulation that may be found
necessary, due for example to differences in
temperature of the water entering at 72 may
be effected by hand by manipulating the
inlet valve 73 to provide a more or less rapid
20 inflow of the cooling liquid according as a
lower or higher temperature is found to be
desirable in the cooling jackets.

The vapor duct 5, 50, 51, 20 leading from
25 the retort or boiler 2 to the delivery point
52 for the condensate, is continuous, and
comprises an upwardly inclined portion con-
taining the primary condenser followed by
the downwardly directed part containing
30 the secondary condenser, so that the con-
densate of the primary condenser flows back-
ward to the boiler, while that of the second-
ary condenser flows forward to and out of
the delivery passage, the separation of the
35 materials taking place in the boiler and pri-
mary condenser.

The vapor dust is shown as provided with
a coupling or separable joint at 500, so that
the primary condenser may be removed for
cleaning, or for substitution by another hav-
ing a modified arrangement, or proportion,
spacing, and perforation, of the plates, if
the nature of the material to be operated
upon renders it desirable.

The tubular body 30 of the primary con-

denser constitutes practically a lining for the 45
upwardly inclined portion 50 of the vapor
pipe leading from the boiler or retort 2, said
primary condenser thus constituting or con-
taining the portion of the vapor duct which
is comprised in the portion 50 of the pipe 50
5, 50, 51, 20, leading from the boiler 2 to
the discharge outlet at 50, which pipe in its
entirety has been referred to as constituting
or containing the vapor duct.

What I claim is:

1. An upwardly inclined tubular chamber
constituting a portion of a vapor duct, com-
bined with a number of plates extending
from the upper wall part way to the lower
wall of said chamber, and foraminous plates 60
extending upward from the lower wall in
the spaces between said plates extending
from the upper wall.

2. An upwardly inclined tubular chamber
constituting a portion of a vapor duct and 65
having a number of plates extending from
the upper wall part way to the lower wall,
combined with foraminous plates extending
upward from the lower wall in some of the
spaces between said plates which extend 70
downward from the upper wall, and plates
in some of said spaces which are imperforate
in their lower portion adjoining the lower
wall of the chamber.

3. A condenser for a still comprising an 75
upwardly inclined tubular chamber pro-
vided with baffle plates extending alternately
from the upper and lower walls thereof, and
a jacket for cooling material surrounding
said chamber.

4. A condenser for a still comprising a
tubular chamber having imperforate baffle
plates extending downward from the upper
wall thereof and foraminous plates alternat-
ing therewith extending upward from the 85
lower wall, combined with a jacket for cool-
ing material surrounding said chamber.
